UNITED STATES PATENT OFFICE.

JOHN A. LENTZ, OF PHOENIX, ARIZONA.

CASTING MACHINE.

Application filed March 27, 1922. Serial No. 547,193.

My invention relates to casting machines adapted for making castings in general, and for making dental castings in particular, of metal, porcelain, or other material suitable for the respective purpose, such as inlays, backings, dummies, cusps, crowns, bridges, plates, saddles, clasps, bars, regulating appliances and the like; and particularly pertains to that class of casting machines in which the metal or material to be cast is melted by a blow-pipe or other suitable means, in a crucible, is poured into a crucible cavity formed in the top of an investment held in a ring or flask containing a mold chamber communicating with the crucible cavity by a sprueway, and is forced through the sprueway into the mold chamber by air or other suitable gas under pressure; or, is melted directly in the crucible cavity, and in like manner forced into the mold chamber.

The objects of the invention are as follows:

First: In making castings, to give the operator a choice, either to melt the material to be cast directly in the crucible cavity of the investment, when heating the investment is an advantage; or, to melt the material in a crucible removed from the investment and automatically pour it into the crucible cavity of the investment, when it is desired to not subject the investment to unnecessary heat.

Second: To give the operator a choice, according to requirement of each case, either to manually manipulate the blow-pipe flame on the crucible, or the crucible cavity of the investment; or, to have the blow-pipe automatically held and moved into and out of position.

Third: To provide a means for regulating the flame producing gases according to various conditions, purposes and modes of use, and to obviate to a great extent repeated regulation to obtain proper mixture of gases at each casting operation.

Fourth: To provide automatic means of shutting off the gases to the extent and at the time desired.

Fifth: To provide a means for automatically producing pressure in the crucible cavity of the investment, after the crucible cavity is sealed by the cap, a definite, predetermined gas pressure to force the molten material into the mold, which pressure, within a predetermined period of time, may gradually be increased to a predetermined

greater pressure, and so maintained as long as desired.

Sixth: To provide a means whereby the port area of the openings through the cap that seals the crucible cavity of the investment, may be varied if deemed desirable.

Seventh: To provide a means for preheating the gas delivered to the sealed crucible cavity.

Eighth: To provide a means for co-ordinating the above automatic movements, so that the movement or operation of one main lever or mechanical means will effect the operation of all.

Ninth: To provide a mechanism whereby, on operation of a lever, a crucible, containing the molten metal or material, may be advanced or retracted relative to a flask and tilted to discharge its contents into the crucible cavity of the flask when in its advanced position, and whereby continued movement of the lever will effect sealing of the crucible cavity after retraction of the crucible; and whereby further continued movement of the lever will automatically admit air or other suitable gas under pressure to the sealed crucible cavity to force the molten metal or material into a mold chamber in the flask, and, if desired automatically increase such pressure, as desired; and whereby return of the lever to its initial position will automatically restore the crucible to its initial position.

With the above stated objects in view, and also such other objects as may subsequently appear, the invention resides in the parts and in the construction, combination, and arrangement of parts hereinafter described and illustrated in the accompanying drawings in which:

Fig. 1 is a perspective view of the machine with parts broken away, with the mechanism set in readiness for operation;

Figs. 2, 3 and 4 are sectional views of various flasks employed in the machine;

Fig. 5 is a view in section and elevation as seen on the line 5—5 of Fig. 1, showing the parts as arranged after operation of the lever to seal the flask and preceding the delivery of air to the flask;

Referring to the drawings more specifically, the several units constituting the assembly of my machine comprise a base unit 15, a gas pressure unit 16, a crucible unit 17, 15 a capping unit 18, a gas valve and blow pipe unit 19, and a flask unit 20.

The base unit.

The base unit comprises a plate formed 20 with a vent opening 21, encircled by a series of annular concentric grooves 22 formed in the upper surface 23 of a base plate. The grooves 22 are connected by radial grooves 24. The grooves and vent opening constitute 25 air passages to permit air to pass from the flask unit, as will later be described. Formed on the base plate, and surrounding the annular grooves 22, is a series of annular beads or walls 25 having aligned openings 30 26, therein forming passageways through the walls 25 leading to a depression 27 in the surface 23. The walls 25 form troughs for the collection of particles of escaped metal, and also constitute flanges for the centering 35 of the flask unit. A flange 28 extends around the outer edge of the base plate, forming a basin throughout the top thereof.

The gas pressure unit.

The gas pressure unit 16, particularly shown in Figs. 1, 5, 6 and 7, includes an ordinary gas pressure regulator 29 adapted for converting a higher pressure into a lower definite pressure and capable of adjustment 45 to deliver different definite pressures with the same resistance offered to gas exit, within the limits of the instrument, by turning an adjustment wheel 40^a projecting from the top of the regulator and provided with two shallow drill holes 40^b for application of a suitable adjustment wrench. There is nothing novel about the regulator, and any regulator, regardless of principle on which it is built, capable of adjustment to deliver different pressures, is applicable.

The chamber within the regulator is connected at one side by a passage to a conduit 31 leading to any suitable source of air, or other suitable gas supply under a pressure in 50 excess of any to be delivered to the investment flask; on the opposite side it is connected by the passageway *a* with T-coupling 30.

The T-coupling has a passage way *b* connecting with the passage *a* of the gas reg-

ulator, in which is disposed an electric heating element 32 adapted to heat the gas flowing through the passage *b*. Supported on brackets 33, is a cylinder 34 having a nipple 35, adjacent one end fitted with a screw 36 70 threaded in the nipple, and adapted to vary the size of a vent 35' formed in the nipple. Mounted in the cylinder is a piston 37 on a rod 38 connected with the adjustment wheel 40^a, as will presently be described; there being a compression spring 39 bearing between the end of the cylinder and the piston, and adapted to advance the latter in the cylinder in opposition to the cushion formed by a body of air, or other fluid, in the cylinder 80 between the piston and the vent; the fluid in the cylinder serving to oppose free movement of the piston under the action of the spring to retard operation of the valve as will later appear. A liquid such as oil may be substituted for the air in the cylinder 34, and by means of a by-pass, the vented liquid returned to the cylinder on the opposite side of the piston without changing the nature of the invention. A handle 40, adjustably fixed at the clamping screw 40^c to the wheel 40^a, is connected by a link 42 to the rod 38, so that as the latter is reciprocated, the wheel 40^a will be turned. Pivoted at *c*, on the cylinder 34, is a trigger device 43 comprising a catch 44 adapted to be engaged with a slot 45 in the rod 38 to hold the latter in an advanced position in opposition to the spring 39; a spring *d*, acting on the trigger 44 to hold the latter in its rod engaging position. A trip lever 46, pivoted at *e*, has a finger on one end engaging the catch 44, and has its opposite end upturned and positioned to be operated, as will presently be described, to trip the catch 44. A lug 40^d, adapted to slide on rod 38, and to be clamped tightly into any position along rod 38 by the clamping screw 40^e, is designed to stop the forward movement of the piston 37 actuated by spring 39 during any part of the stroke, thereby stopping the rotation of wheel 40^a and maintaining the pressure thus far produced. A two-way valve 47, mounted on an operating lever 48 pivoted at *f*, is provided with a disc 49 fixed to the valve stem 47^a, 100 and formed on the edge of the disc as a tooth 50 and handle 51; projecting from the disc is a pin 52, adapted to engage the trip lever 46 on turning of the disc 49 when the lever 48 is disposed in its horizontal locked position. A stop pin 53 is fastened in the casing of the valve 47 to limit travel of the disc 49, being arranged in the path of travel of the tooth 50. Pivoted at *g*, on the lever 48, is a trip arm 54 adapted to engage the tooth 50, and extending between the handle 51 and down turned arm 55 on the trip arm 54 is a coil spring 56, tensioned to maintain the trip arm in engagement with the disc, and to exert a pull on the handle 51 to rock 110

115 the disc 49 when the lever 48 is disposed in its horizontal locked position. A stop pin 53 is fastened in the casing of the valve 47 to limit travel of the disc 49, being arranged in the path of travel of the tooth 50. Pivoted at *g*, on the lever 48, is a trip arm 54 adapted to engage the tooth 50, and extending between the handle 51 and down turned arm 55 on the trip arm 54 is a coil spring 56, tensioned to maintain the trip arm in engagement with the disc, and to exert a pull on the handle 51 to rock 120

125 the disc 49 when the lever 48 is disposed in its horizontal locked position. A stop pin 53 is fastened in the casing of the valve 47 to limit travel of the disc 49, being arranged in the path of travel of the tooth 50. Pivoted at *g*, on the lever 48, is a trip arm 54 adapted to engage the tooth 50, and extending between the handle 51 and down turned arm 55 on the trip arm 54 is a coil spring 56, tensioned to maintain the trip arm in engagement with the disc, and to exert a pull on the handle 51 to rock 130

the valve on disengaging the trip arm from the disc. A locking lever 57 is pivotally mounted at *h* on the base plate and is held forwardly by a plate spring 58, and formed on the locking lever is a shoulder 59, and formed above the shoulder is a curved face 60. A dependent bracket 61 is fixed to the operating lever 48 and has an elongated slot 62 disposed to be engaged by the shoulder 59; the bracket being adapted to engage the curved face 60 and push the lever 57 backward on downward movement of the operating lever. The arm 55 of the trip arm 54 is formed with a projection 63, adapted to be moved by contact therewith of the outer end of the shoulder 59 to trip the trip arm 54 and release the disk 49, at, or adjacent to, the termination of the down stroke of the operating lever 48. The casing of the valve 47 is formed with a passage 64, in which the cut-off valve on the valve stem 47^a is arranged, the valve being formed with a part 65 adapted to be moved in and out of register with the passage 64. The port 65 is closed to the passage 64 when the disc 49 is engaged by the trip arm and is designed to be opened to the passage 64 on rotation of the valve under action of the spring 56. One end of the passage 64 is connected by a flexible tube 56 to the passage *b* in the T-coupling 30, and the other end of the passage 64 connects with a flexible tube 67 leading to a tube 68 on a cap 69 of the capping unit 18; the tube 68 opening through a port 70 to the interior of the cap.

A pressure gage A is connected to the T-coupling 30 to indicate the air pressure in passage *b*.

The flask unit.

The flask unit comprises an open ended tubular casing 73 containing an investment 74 formed of porous material provided with a mole cavity 75 and a sprue way 76; the upper surface of the investment being concave to form a crucible cavity to receive molten metal as is common in devices of this character. The flask may be formed in any desired manner according to the work to be performed, and is designed to be seated on the base plate and centered over the vent 21; the flask either being seated directly on the base plate as shown in Figs. 2, 4 and 5 or seated on a fillet block as shown in Fig. 3, in event the flask is short in length.

The capping unit.

The capping unit comprises the cap 69 which has a recessed under side fitted with a gasket 78 adapted to seat on the upper edge of the casing 73 to seal the flask. This cap 69 is formed with a yoke 79 which extends astride the operating lever 48, and is connected to the latter by trunnions 80 on the lever 48 projecting into elongated slots 81 in

the yoke, whereby the lever 48 may have downward movement relative to the cap, after the latter has been seated on the flask. A spring 82 is interposed between the lever and the cap as a means for normally maintaining the trunnions in the outer end of the slots and for yieldably opposing the movement of the lever 48 after the cap is seated. The cap is formed with a distributing chamber 83 with which the port 70 communicates; this chamber having a perforated wall 84 opening to the underside of the cap. A small circular disc 84' with openings registering with those on the under surface of perforated wall 84, is pivoted centrally against the under surface of the perforated wall 84, so that by rotating the disc 84', the openings in wall and disc may be brought in and out of register, and thereby effect the volume of air or gas delivered to the crucible cavity.

The crucible unit.

The crucible unit 17 embodies a crucible 85 carried on a shank 86 fitted on a stem 87 mounted for reciprocal and rotary movement in a sleeve 88 on a spindle 89 turnable in a standard 90 fixed on the base plate; the crucible thus being mounted to be advanced and retracted with a reciprocating movement of the spindle 89, and to be tilted by turning the shank and stem in the sleeve 88. The means for operating the crucible embodies a cam cylinder 91 mounted on a rock shaft 92, on which the operating lever 48, pivoted at *f*, is rigidly mounted. The cam cylinder 91 is formed with a cam recess 93 of substantially triangular form, and mounted within the recess is a spring tensioned guide frog 94 of substantially triangular form, one corner of which normally abuts against the side wall of the cam recess, and the sides of which are spaced from the walls of the recess, forming a channel which is interrupted at one point by the frog. The end of the stem 87 is fitted with a knob 95 which projects into the recess 93 in position to be engaged by the walls of the latter in such manner that, as the cylinder is turned on initial downward movement of the lever 48, the knob 95 will be caused to traverse an inclined portion of the cam channel by action of the guide frog so as to swing the crucible inwardly toward the flask during the partial downward movement of the lever; the knob moving into a reverse inclined portion of the cam channel on continued downward movement of the operating lever to cause the crucible to be retracted relative to the flask; and the knob traversing a circumferential portion of the cam channel throughout the remainder of the down stroke of the lever to maintain the crucible in its retracted position. The knob traverses a circumferential portion of the channel on upward

movement of the lever and passes to the other side of the frog as the lever returns to its uppermost position.

As a means for effecting tilting of the crucible when in its advanced position over the flask a prong 96 on the standard 90 engages a downturned finger 97 on the shank 86 as the latter moves forward in such manner as to rock the latter to tilt the crucible downwardly. A second prong 98 engages the finger 97 on rearward movement of the shank to restore the crucible to a horizontal position and to maintain it in such position until acted on by the prong 96. The crucible and its mountings may be removed when it is desirable to melt the material to be cast directly in the crucible cavity of the flask.

The gas valve and the blow pipe unit.

20 Mounted on the base plate is a tubular standard 99 constituting a casing for a rotary valve 100 having a pair of horizontal angular ports 101 and 102 adapted to be moved in and out of register with intake ports 103 and 104, and outlet ports 105 and 106. The horizontal angular port 101 is continued for a short distance on the external surface of the rotary valve 100 as a groove of gradually diminishing cross area from the 25 port openings in a direction opposite to that in which rotary valve 100 is turned to shut off the gases. The inlet port 103 connects with a source of a suitable combustible gas supply through a regulating needle valve 107 and a cut-off valve 108.

The intake port 104 connects with a source of a suitable oxidizing gas as nitrous oxide, oxygen or air, through a regulating needle valve 109. In accordance with the manner 40 in which it is desired to operate this blow pipe, the respective gas supplies to 103 and 104 may be reversed. The outlet ports 105 and 106 connect with a common passage 110 connecting with a flexible conduit 111 leading to a blow pipe 112 supported in an adjustable bearing 113 on a standard 114 projecting axially from the valve 100, so as to turn with the latter and effect an oscillating 45 movement of the blow pipe. As a means 50 for effecting movement of the valve 100 to automatically close the ports and cut off the supply of gases to the blow pipe, a pin 115 is provided on the valve 100, adapted to be positioned to project in the path of 55 travel of a pin mounted on the end face of the cam cylinder is turned by depressing the operating lever 48, the pin 116 will engage the pin 115 and cause the valve 100 to turn a partial revolution during the initial movement of the cam cylinder, shutting off the 60 supply to 102 and reducing the supply to 101. As the simultaneous shutting off of both gas supplies is likely to cause an explosion of gases, where oxygen is one of the 65 gases employed, it is advisable to allow at

least a partial flow of gas through 101 for a limited time. Where the combustible gas is connected with 103, this results in a pilot light remaining burning, which can be shut off by the cut-off 108, or left burning for 70 the next operation. The lever 48 being in its uppermost position, valve 100, when gradually brought back to operating position, with pin 115 in contact with pin 116, the combustible gas supply is again restored 75 to the proper flow, as maintained by the already regulated needle valve 107, and likewise the oxidizing gas supply is again restored to the proper flow, as maintained by the already regulated needle valve 109. Where the supply of gases is reversed, the 80 operation of rotary valve 100, by the movement of main lever 48, is to shut off the combustible gas and the flame and to reduce the flow of the oxidizing gas, which is then turned off by cut-off 108. If desired the effect of turning off the cut-off 108 can be automatically accomplished by two additional pins similar to 115 and 116 properly positioned on valve 100 and on the end face of cam cylinder 91, respectively, and adapted to impart an additional revolving movement to valve 100 near the completion of the downward movement of the lever 48 and carry the grooves extending from the parts of 101 also out of register with port 103.

The blow pipe 112 may, if desired, be moved from its support and manually operated.

Operation.

In the operation of the invention, several preliminary manual adjustments are employed before starting the mechanism in operation, to-wit: (a) The operating lever 48 is moved to its uppermost position as shown in Fig. 1, thus retracting the cam cylinder to position the crucible in a position to one side of the flask.

(b) The gas pressure regulator 29 is turned on, valve 47 is disposed in its closed position, with the trip arm engaging the disc 49 to hold the valve closed.

(c) Arm 40 being released from its grip on wheel 40^a by unscrewing screw 40^c by 115 means of a wrench inserted into drill holes 40^b, wheel 40^a is turned clockwise, as required, until pressure gauge A shows the desired initial pressure to be delivered. Maintaining wheel 40^a in this position, arm 40 is 120 placed into operating position with trigger 44 engaged in slot 45 on rod 38, with spring 39 under tension. Screw 40^c is now tightened, clamping arm 40 firmly to wheel 40^a. With an investment filled flask for testing 125 purposes in position, lever 48 is brought down and flask sealed, automatically opening valve 47, tripping the trigger 44 and setting rod 38 in motion, and thereby revolving wheel 40^a and increasing the pres-

sure delivered through the regulator. When the final desired pressure is reached as indicated by the pressure gauge, rod 38 is held in this position and lug 40^d moved 5 against the cylinder 34 and clamped in position by turning the screw 40°, thus fixing the maximum pressure delivered through the regulator. By making several testings, the screw 36 is adjusted to regulate the vent 35' 10 so as to make the desired time elapse between the delivery of the initial pressure to the time maximum pressure is reached. As there is little occasion for frequent changes in adjustment of pressure and time 15 before the maximum is reached, when this adjustment is once made, no further adjustment is necessary except for special purposes. These adjustments, therefore, having been made, arm 40 is placed in operating 20 position with trigger 44 engaged in slot 45 in rod 38.

(d) A desired flask filled with investment, its upper surface formed into a crucible cavity connecting by a sprueway to 25 the mold chamber within the investment, is centered on the base plate and positioned to receive the contents of the crucible and to be sealed by the cap 69 on downward movement of the lever 48.

(e) The current to the heating element 32 is turned on.

(f) The gas control valve 100 is positioned manually to open communication between the inlet and outlet ports and dispose the blow pipe nozzle over the crucible by opening cut-off valve 108 and turning on the supply of combustible and oxidizing gases and regulating them by needle valves 107 and 109, an inflammable gaseous mixture 40 is delivered to the blow pipe. The metal or material to be melted is placed in the crucible and the gas discharged from the blow pipe being ignited the blow pipe is positioned manually or mechanically to effect 45 melting of the metal.

(g) When the material becomes melted the operator moves the lever 48 downward which turns the cam cylinder 91 and operates through the latter to immediately turn the gas control valve 100, and at the same time move the blow pipe nozzle clear out of the crucible. During this movement of the cam cylinder, the crucible is carried forward and caused to deposit its contents into 55 the flask. Continued downward movement of the lever causes the crucible to be retracted clear of the flask in sufficient time to permit the cap 69 on the lever to move into position on the flask as the lever nears 60 the termination of its down stroke. The moment the lever assumes a position with the cap firmly seated on the flask, it is engaged by the locking lever 57 and held against upward movement; the projection 65 59 on lever 57 throws the trip arm 54 out of

engagement with the disc on the valve 47, so that the latter will be turned under the action of spring 56 to permit air or other gas used to flow to the flask. Turning of the disc rocks the lever 46 and lifts the 70 trigger 44 out of engagement with the slot 45 in rod 38 and allows spring 39 to slowly turn the wheel 40^a until lug 40^d stops the movement of rod 38 in the position for delivery of desired maximum pressure. 75

The air, entering the flask, operates to force the molten metal through the sprue-way 76 into the mold chamber 75, the air exhausting through the porous investment and escaping through the vent 21. The air delivered to the flask, in flowing through the passage b, will be heated by the action of the heating coil so as to prevent or minimize the chilling effect on the molten metal or material in the flask. The application 80 of moderate initial pressure followed by the gradual delivery of increased pressure, has the effect of absolutely avoiding back pressure, of enabling the first layer of material to be placed against the walls of the mold at 85 a light pressure without injury to delicate and frail portions and without distortion, and when the film of material next to the mold wall is somewhat congealed, to permit a greater pressure to be delivered without injury than could be safely used where one 90 pressure is applied throughout.

The locking lever 57 is then manually retracted in opposition to spring 58, whereupon the operating lever 48 may be 100 manually returned to its uppermost position, which operation has no effect other than to restore the knob 95 to its position in the lower part of the cam slot and restore the crucible to its initial operating position. No action will be had on the valve 100, as 105 the pin 116 on the cam cylinder will move away from pin 115 on its retracted movement.

I realize that there is nothing novel in the following combination, namely: a flask containing a mold chamber connected by a sprueway to a crucible cavity; a cap adapted for sealing said flask; a means for sealing said flask with said cap; a means for providing gas under pressure in the sealed crucible cavity to force molten material from the crucible cavity into the mold chamber; a blow pipe for melting the material to be cast; a means for supporting the blow pipe in position; a means for regulating the mixture of gases to the blow pipe; a means for shutting off the gases to the blow pipe; and a means for turning the blow pipe out of interference; so I do not claim this combination or any one that can be made by rearrangement of the various elements in this combination as novel, but I do claim as novel the following:

1. In a casting machine, the combination

of a flask containing a mold chamber connected by a sprue way with a crucible cavity in said flask; a cap adapted to seal said crucible cavity; means for sealing said crucible cavity with said cap; means for providing gas under pressure in said sealed crucible cavity to force molten material from said crucible cavity into said mold chamber; a crucible in which the material to be cast is melted, said crucible being separate and distinct from said crucible cavity and adapted to empty its molten contents into said crucible cavity; and means for automatically causing said crucible to empty its molten contents into said crucible cavity.

2. In a casting machine, the combination of a flask containing a mold chamber connected by a sprue way with a crucible cavity in said flask; a cap adapted to seal said crucible cavity, means for sealing said crucible cavity with said cap; means for initially providing gas under relatively low pressure in said sealed crucible cavity to force molten material from said crucible cavity into said mold chamber; and automatic means for gradually increasing the initial gas pressure provided in said sealed crucible cavity.

3. In a casting machine, the combination of a flask containing a mold chamber connected by a sprue way with a crucible cavity in said flask; a cap adapted to seal said crucible cavity; means for sealing said crucible cavity with said cap; means for providing gas under pressure in said sealed crucible cavity, to force molten material from said crucible cavity into said mold chamber; a crucible in which the material to be cast is melted, said crucible being separate and distinct from said crucible cavity and adapted to empty its molten contents into said crucible cavity prior to the sealing thereof, means for causing said crucible to empty its molten contents into said crucible cavity; and means for automatically increasing the initial gas pressure provided in said crucible cavity.

4. In a casting machine, the combination of a flask containing a mold chamber connected by a sprue way with a crucible cavity in said flask; a cap adapted to seal said crucible cavity; means for sealing said crucible cavity with said cap; means for providing gas under pressure in said sealed crucible cavity to force molten material from said crucible cavity into said mold chamber; a crucible in which the material to be cast is to be melted, said crucible being separate and distinct from said crucible cavity and adapted to empty its molten contents into said crucible cavity prior to the sealing thereof; means for causing said crucible to empty its molten contents into said crucible cavity; and means for automatically increasing the gas pressure provided in said sealed crucible

cavity, from a predetermined initial pressure to a predetermined final pressure.

5. In a casting machine, the combination of a flask containing a mold chamber connected by a sprue way with a crucible cavity in said flask; a cap adapted to seal said crucible cavity; means for sealing said crucible cavity with said cap; means for providing gas under pressure in said sealed crucible cavity to force molten material from said crucible cavity into said mold chamber; a crucible in which the material to be cast is melted, said crucible being separate and distinct from said crucible cavity, and adapted to empty its molten contents into said crucible cavity prior to the sealing thereof; means for causing said crucible to empty its molten contents into said crucible cavity; and means for automatically increasing the gas pressure provided in said sealed crucible cavity from a predetermined initial pressure to a predetermined final pressure, within a predetermined period of time.

6. In a casting machine, the combination of a flask containing a mold chamber connected by a sprue way with a crucible cavity in said flask; a cap adapted to seal said crucible cavity; means for sealing said crucible cavity with said cap; means for providing gas under pressure in said sealed crucible cavity to force molten material from said crucible cavity into said mold chamber; a crucible in which the material to be cast is melted, said crucible being separate and distinct from said crucible cavity and adapted to empty its molten contents into said crucible cavity prior to the sealing thereof; means for causing said crucible to empty its molten contents into said crucible cavity; and means for preheating said gas provided in said sealed crucible cavity.

7. In a casting machine, the combination of a flask containing a mold chamber connected by a sprue way with a crucible cavity in said flask; a cap adapted to seal said crucible cavity; means for sealing said crucible cavity with said cap; means for providing gas under pressure in said sealed crucible cavity to force molten material from said crucible cavity into said mold chamber; means for automatically increasing the initial gas pressure provided in said crucible cavity; and means whereby the gas provided in said crucible cavity is pre-heated.

8. In a casting machine, the combination of a flask containing a mold chamber connected by a sprue way with a crucible cavity in said flask; a cap adapted to seal said crucible cavity; means for sealing said crucible cavity with said cap; means for providing gas under pressure in said sealed crucible cavity to force molten material from said crucible cavity into said mold chamber; means for automatically increasing the gas pressure provided in said sealed crucible

cavity, from a predetermined initial pressure to a predetermined final pressure; and means whereby the gas provided in said crucible cavity is pre-heated.

- 5 9. In a casting machine, the combination of a flask containing a mold chamber connected by a sprueway with a crucible cavity in said flask; a cap adapted to seal said crucible cavity; means for sealing said crucible cavity with said cap; means for providing gas under pressure in said sealed crucible cavity to force molten material from said crucible cavity into said mold chamber; means for automatically increasing the gas 10 pressure provided in said sealed crucible cavity, from a predetermined initial pressure to a predetermined final pressure, within a predetermined period of time; and means whereby the gas provided in said crucible cavity is pre-heated.

- 10 10. In a casting machine, the combination of a flask containing a mold chamber connected by a sprueway with a crucible cavity in said flask; a cap adapted to seal said crucible cavity; means for sealing said crucible cavity with said cap; means for providing gas under pressure in said sealed crucible cavity, to force molten material from said crucible cavity into said mold chamber; a 15 crucible in which the material to be cast is melted, said crucible being separate and distinct from said crucible cavity and adapted to empty its molten contents into said crucible cavity; means for causing said crucible cavity to empty its molten contents into said crucible cavity prior to the sealing thereof; means for automatically increasing the initial gas pressure provided in said sealed crucible cavity; and means whereby the gas 20 provided in said crucible cavity is pre-heated.

- 11 11. In a casting machine, the combination of a flask containing a mold chamber connected by a sprueway with a crucible cavity in said flask; a cap adapted to seal said crucible cavity; means for sealing said crucible cavity with said cap; means for providing gas under pressure in said sealed crucible cavity to force molten material from said crucible cavity into said mold chamber; a 25 crucible in which the material to be cast is melted, said crucible being separate and distinct from said crucible cavity and adapted to empty its molten contents into said crucible cavity; and means for causing said crucible cavity to empty its molten contents into said crucible cavity prior to the sealing thereof; means for automatically increasing the gas 30 pressure provided in said sealed crucible cavity, from a predetermined initial pressure to a predetermined final pressure; and means for preheating said gas provided in said sealed crucible cavity.

- 12 12. In a casting machine, the combination of a flask containing a mold chamber connected by a sprueway with a crucible cavity

in said flask; a cap adapted to seal said crucible cavity; means for sealing said crucible cavity with said cap; means for providing a gas under pressure in said sealed crucible cavity to force molten material from said crucible cavity into said mold chamber; a crucible in which the material to be cast is melted, said crucible being separate and distinct from said crucible cavity and adapted to empty its molten contents into said crucible cavity; means for causing said crucible to empty its molten contents into said crucible cavity prior to the sealing thereof; means for automatically increasing the gas pressure provided in said sealed crucible cavity, from a predetermined initial pressure to a predetermined final pressure, within a predetermined period of time; and means whereby the gas provided in said crucible cavity is pre-heated.

13. In a casting machine, the combination of a flask containing a mold chamber connected by a sprueway with a crucible cavity in said flask; a cap adapted to seal said crucible cavity; means for sealing said crucible cavity with said cap; means for providing gas under pressure in said sealed crucible cavity to force molten material from said crucible cavity into said mold chamber; a crucible in which the material to be cast is melted, said crucible being separate and distinct from said crucible cavity and adapted to empty its molten contents into said crucible cavity; means for automatically causing said crucible to empty its molten contents into said crucible cavity; and means for melting said material to be cast.

14. In a casting machine, the combination of a flask containing a mold chamber connected by a sprueway with a crucible cavity in said flask; a cap adapted to seal said crucible cavity; means for sealing said crucible cavity with said cap; means for providing gas under pressure in said sealed crucible cavity to force molten material from said crucible cavity into said mold chamber; a crucible in which the material to be cast is melted, said crucible being separate and distinct from said crucible cavity and adapted to empty its molten contents into said crucible cavity; and means for causing said crucible to empty its molten contents into said crucible cavity, a blow pipe; a turnable valve for directing the flow of gases to said blow pipe, and adapted, on turning, to shut off said gases; and means for automatically turning said valve.

15. In a casting machine, the combination of a flask containing a mold chamber connected by a sprueway with a crucible cavity in said flask; a cap adapted to seal said crucible cavity, means for sealing said crucible cavity with said cap; means for providing gas under pressure in said sealed crucible cavity to force molten material from

said crucible cavity into said mold chamber; a crucible in which the material to be cast is melted, said crucible being separate and distinct from said crucible cavity and adapted to empty its molten contents into said crucible cavity; means for causing said crucible to empty its molten contents into said crucible cavity, a blow pipe; a turnable valve for directing the flow of gases to said blow pipe; said valve being adapted for mounting said blow pipe thereon, and, on turning, to shut off said gases and turn blow pipe out of interference and means for automatically turning said valve.

15 16. In a casting machine, the combination of a flask containing a mold chamber connected by a sprueway with a crucible cavity in said flask; means for melting and delivering metal to be cast to the crucible cavity; a cap adapted to seal said crucible cavity; means for sealing said crucible cavity with said cap; means for providing gas under relatively low pressure in said sealed crucible cavity to force molten material from said crucible cavity into said mold chamber; and automatic means for gradually increasing the initial gas pressure provided in said sealed crucible cavity.

17. In a casting machine, the combination of a flask containing a mold chamber connected by a sprueway with a crucible cavity in said flask; means for melting and delivering the metal to be cast to the crucible cavity including a crucible, a blow pipe; a turnable valve for directing flow of gases to said blow pipe adapted to be turned to shut off said gases, means for automatically turning said valve, a cap adapted to seal said crucible cavity; means for sealing said crucible cavity with said cap; means for providing gas under relatively low pressure in said sealed crucible cavity to force material from said crucible cavity into said mold chamber; and automatic means for gradually increasing the initial gas pressure provided in said sealed crucible cavity.

18. In a casting machine, the combination of a flask containing a mold chamber connected by a sprueway with a crucible cavity in said flask; means for melting and delivering the metal to be cast to the crucible cavity including a crucible, a blow pipe, a turnable valve for directing the flow of gases to said blow pipe, said valve carrying said blow pipe and adapted on turning to shut off said gases and to turn said blow pipe, and means for automatically turning said valve; a cap adapted to seal said crucible cavity; means for sealing said crucible cavity with said cap; means for providing gas under pressure in said sealed crucible cavity to force molten material from said crucible cavity into said mold chamber; and means for automatically in-

creasing the initial gas pressure provided in said sealed crucible cavity.

19. In a casting machine, the combination of a flask containing a mold chamber connected by a sprueway with a crucible cavity in said flask; a cap adapted to seal said crucible cavity, means for sealing said crucible cavity with said cap; means for providing gas under pressure in said sealed crucible cavity to force molten material from said crucible cavity into said mold chamber; a crucible in which the material to be cast is melted, said crucible being separate and distinct from said crucible cavity and adapted to empty its molten contents into said crucible cavity; and means for causing said crucible to empty its molten contents into said crucible cavity; means for automatically increasing the initial gas pressure provided in said sealed crucible cavity; and means for melting said material to be cast.

20. In a casting machine, the combination of a flask containing a mold chamber connected by a sprueway with a crucible cavity in said flask; a cap adapted to seal said crucible cavity; means for sealing said crucible cavity with said cap; means for providing gas under pressure in said sealed crucible cavity to force molten material from said crucible cavity into said mold chamber; a crucible in which the material to be cast is melted, said crucible being separate and distinct from said flask and adapted to empty its molten contents into said crucible cavity; means for causing said crucible to empty its molten contents into said crucible cavity; means for automatically increasing the initial gas pressure provided in said sealed crucible cavity; and means for melting said material to be cast.

21. In a casting machine, the combination of a flask containing a mold chamber connected by a sprueway with a crucible cavity in said flask; a cap adapted to seal said crucible cavity; means for sealing said crucible cavity with said cap; means for providing gas under pressure in said sealed crucible cavity to force molten material from said crucible cavity into said mold chamber; a crucible in which the material to be cast is melted, said crucible being separate and distinct from said crucible cavity and adapted to empty its molten contents into said crucible cavity; means for causing said crucible to empty its molten contents into said crucible cavity; means for automatically increasing the initial gas pressure provided in said crucible cavity; a blow pipe; a turnable valve for directing the flow of gases to said blow pipe, and adapted, on turning, to shut off said gases; and means for automatically turning said valve.

22. In a casting machine, the combination of a flask containing a mold chamber

- connected by a sprue way with a crucible cavity in said flask; a cap adapted to seal said crucible cavity; means for sealing said crucible cavity with said cap; means for 65
 5 providing gas under pressure in said sealed crucible cavity to force molten material from said crucible cavity into said mold chamber; a crucible in which the material to be cast is melted, said crucible being separate and distinct from said crucible cavity and adapted to empty its molten contents into said crucible cavity; means for causing said crucible to empty its molten contents into said crucible cavity; means for automatically increasing the initial gas pressure provided in said sealed crucible cavity; a blow pipe; a turnable valve for directing the flow of gases to said blow pipe, said valve being adapted for mounting said blow 70
 10 pipe thereon, and, on turning, to shut off said gasses and turn said blow pipe out of interference; and means for automatically turning said valve.
 15 23. In a casting machine, the combination of a flask containing a mold chamber connected by a sprue way with a crucible cavity in said flask, a cap adapted to seal said crucible cavity; means for sealing said crucible cavity with said cap; a gas feed 75
 20 line connected to a source of gas under pressure, and adapted to deliver gas to said sealed crucible cavity; a gas regulator in said gas feed line, said regulator being adapted for adjustment to deliver any degree of required pressure, and means for automatically causing said regulator to deliver a gradually increasing degree of pressure from a predetermined initial pressure to a predetermined final pressure in a predetermined period of time.
 25 24. In a casting machine the combination of a flask containing a mold chamber connected by a sprue way with a crucible cavity in said flask; a cap adapted to seal said crucible cavity; means for sealing said crucible cavity with said cap; a gas feed line connected with a source of gas under pressure and adapted to deliver gas to said sealed crucible cavity; a gas regulator in said gas 80
 30 feed line, said regulator being adapted for adjustment to deliver any degree of required pressure; a piston, a cylinder in which said piston is mounted, adapted to form a fluid cushion to retard advanced movement of said piston; a spring acting on said piston to advance the latter; connections between said piston and regulator, whereby advanced movement of the said piston will effect adjustment of said regulator from one degree 85
 35 of delivered pressure to another; means for holding said piston in a retracted position in opposition to said spring; automatic means for releasing said piston from its retracted position, stopping the advanced 90
 40 movement of said piston at a predetermined point, and for gradually venting the fluid cushion opposing the advance movement of the piston.
 45 25. In a casting machine of the class described, an operating lever, a flask, a cap operable by said lever for sealing said flask, a crucible pivoted to rock horizontally and tilt vertically; means whereby initial movement of said lever will advance said crucible and tilt it over said flask so as to deposit its molten contents into said flask, and whereby continued movement will retract said crucible before the cap is positioned to seal the flask.
 50 26. In a casting machine of the class described, an operating lever, a flask, a cap, operable by said lever for sealing said flask; a crucible pivoted to rock horizontally and tilt vertically; means whereby initial movement of said lever will advance said crucible and tilt it over said flask, so as to deposit its molten contents into said flask, and whereby continued movement will retract said crucible before the cap is positioned to seal the flask; and whereby the whole cycle of movement of said lever, from its initial position to that in which the flask is sealed, and back to the starting position of said lever, will restore said crucible to its initial 95
 55 operating position.
 60 27. In a casting machine of the class described, an operating lever, a flask, a cap operable by said lever for sealing said flask, a crucible adapted to empty its molten contents into said flask, means whereby initial movement of said lever will cause said crucible to empty its molten contents into said flask, and whereby continued movement will retract said crucible out of interference with the positioning of said cap to seal said flask.
 65 28. In a casting machine of the class described, an operating lever, a flask, a cap operable by said lever for sealing said flask, a crucible adapted to empty its molten contents into said flask, means whereby initial movement of said lever will cause said crucible to empty its molten contents into said flask, and whereby continued movement will retract said crucible out of interference with the positioning of said cap to seal said flask; and whereby the whole cycle of movement of said lever, from its initial position to that in which the flask is sealed, and back to the starting position of said lever, will restore said crucible to its initial operating position.
 70 29. In a casting machine of the class described, a flask, a cap for said flask; and means for automatically delivering gas under pressure to said flask, adapted to deliver an initial charge of gas at a relatively low 100
 75 pressure, followed by a supply of gas of gradually increasing pressure.
 80 30. In a casting machine of the class de-

scribed, an operating lever, a crucible for closing said valve whereby the supply pivoted to swing horizontally; a blow pipe; a turnable valve for directing the flow of gases into said blow pipe, and on which the 5 blow pipe is mounted, forming a pivotal support for the latter; means operable by said lever for swinging said crucible and

10
automatically shutting off on advanced movement of the crucible; and means for effecting tilting of the crucible when the latter is in its advanced position.

JOHN A. LENTZ.
